LOCOMOTIVE DRAFT APPLIANCE

Adolf Giesl-Gieslingen, New York, N. Y.

Application February 13, 1932, Serial No. 592,710

8 Claims. (Cl. 230—96)

My present invention relates to draft appliances for steam locomotives, in which the draft required for the fire is created by suction obtained from the exhaust steam.

5 In such draft appliances, a steam jet, mainly the exhaust from the locomotive driving engine, is used to create a partial vacuum in the so-called smokebox of the boiler, thereby pumping the air and products of combustion through the 10 boiler and discharging them through the smokestack into the atmosphere. Locomotive boilers require for their operation a far stronger draft than any other commercially used steam generator. When working at full capacity, the combustion 15 gases pass through the boiler tubes at a speed of 150 feet per second and more, and through the smokestack at speeds often exceeding 600 feet per second. Therefore, large amounts of energy are required to produce such draft, representing substantial percentages 20 (often 30% and more) of the total locomotive performance, that would otherwise be available in form of useful work at the drawbar. The problem of producing locomotive boiler draft in 25 an economical manner has always been in the foreground and consequently, inventive ingenuity has been attracted thereto to a special degree, creating a great variety of devices within a century of development. However, the subject has 30 so far evaded a satisfactory solution. It has not been possible to devise general rules for the design of such draft appliances and the subject continues to be vital to an even higher degree than before, since modern locomotives are working 35 harder and are suffering greater losses from back pressure caused by inefficient draft appliances, and are wearing out too quickly some of the devices that have been developed to increase efficiency.

40 It is the purpose of my invention to create draft appliances of new and greatly improved general characteristics and utility, wherefore I primarily seek the following objects:

1. Maximum efficiency of action.

45 2. Stronger draft when the locomotive is starting or working heavily at slow speed.

3. Maximum lateral expansion or divergence of the exhaust steam jet, effected with a minimum or no additional expenditure of energy.

50 4. Minimum wear of the device by minimizing the grinding action of cinders passing through.

Object 1 may be analyzed and divided into the following requirements, which are being fulfilled by my invention:

55 (a) Mixing the exhaust steam with the com-

bustion gases after a relatively high speed has been imparted to said gases, thereby minimizing energy losses due to the unavoidable shock occurring when gas and steam come in contact with each other,

(b) Affording thorough mixture of gas and steam by forcing the former into the steam current and providing for sufficient time for the currents to thereafter adequately equalize,

(c) Providing a divergent path for gas and steam during the major part of the processes of mixture and of equalization between gas and steam currents,

(d) Dividing the processes of entrainment and consequent mixture of gas and steam into two 15 or more sections by the use of intermediate nozzles, thereby further decreasing energy losses and providing suction at different points along the length of the device, which latter feature usually has a beneficial effect upon the steam boiler.

Object 2 is designed to avoid the usual tendency of the boiler pressure to fall off when a locomotive with the presently known draft appliances is starting a heavy train.

Object 3 is of vital importance for the following well-known reasons, discussed in more detail in my co-pending application Serial No. 441,894 now Patent No. 1,869,991, Aug. 2, 1932: To function properly, a locomotive smokestack must be completely filled by the exhaust steam jet, at least near the outlet or top. Therefore, the cross-sectional area of such smokestack near the top must never be larger than that of said exhaust jet. Due to the natural divergence of a steam jet escaping from an orifice, almost any desired 30 area may be filled by the jet at the proper distance from said orifice, but locomotives have reached proportions which, as a rule, make it impossible to provide sufficiently wide smokestacks since there is not enough room for the required 35 length of the draft appliance. Therefore, it is quite general practice to employ some means of spreading the exhaust steam which involve considerable losses in energy, while my invention promotes lateral expansion of the steam jet without any harsh and harmful coercive spreading.

Object 4 requires no further discussion since it is well known that cinders entrained by the steam jet have a highly abrasive action. Therefore, I design and locate the various parts of my 50 invention in such a way as to largely avoid direct contact with the steam jet.

To these ends, I provide the draft appliance with one or more intermediate nozzles diverging 55

toward their outlets, and combine various other features as hereinafter set forth.

There is great confusion among those skilled in the art as to the characteristics promoting optimal function of a draft appliance. After nearly a decade of wide study, I established rules embracing most of the above enumerated requirements as well as some further features which will appear later in this specification, and I succeeded in discovering simple means by which my findings can most effectively be put into practice. In the state of the art prior to my invention, however, I know of no device that fulfills any of the requirements established by me without antagonizing part of said requirements to the detriment of efficiency and utility.

In the accompanying drawings, Fig. 1 is a longitudinal section through a conventional construction of locomotive smokebox wherein one embodiment of my invention is shown. Fig. 2 is a transverse section through the same smokebox, corresponding to Fig. 1.

Figures 3 and 4 are diagrammatical sketches of preferred forms of my invention, in longitudinal section.

Fig. 5 is a diagrammatical sketch of a modified exhaust nozzle, and Fig. 6 a sketch of a modified intermediate nozzle, both shown in longitudinal section.

Fig. 7 is a diagrammatical sketch of a preferred form of my invention in which I use an intermediate nozzle adapted to split the exhaust steam jet. Fig. 8 is a section through the intermediate nozzle shown in Fig. 7 along the line 8—8, Fig. 9 is a top view of said intermediate nozzle, and Fig. 10 a top view of a modified form of such intermediate nozzle.

Figures 11, 12, and 13 illustrate an example of an incorporation of my invention in a draft appliance of other than circular (oblong) cross section, Fig. 11 being a diagrammatical longitudinal section, Fig. 12 a like transverse section at a right angle thereto, and Fig. 13 a cross section through the intermediate nozzle along the line 13—13 in Fig. 11.

Referring to Figures 1 and 2: A conventional locomotive boiler is shown merely as an illustration, without intent to limit the application of my invention to any particular construction of boiler. The cylindrical barrel 1 contains the fire tubes 2 through which the combustion gases pass into the smokebox 3 as indicated by the arrows 4, 5. A smokestack 6 is mounted on top of the smokebox. The exhaust nozzle 7 is, as usual, mounted on the standpipe 8 into which the exhaust steam enters from below, upon which said steam is discharged through the stack 6, entraining the surrounding combustion gases. All the foregoing features are well known.

Before entering the stack, the exhaust steam passes through the intermediate nozzle 9 which may for example be supported on the standpipe by means of arms 10 and the flange 11. No nettings nor baffle plates for arresting sparks are shown and the arrangement may thus be used for an oil-burning locomotive, but of course, any type of spark arrester may be incorporated if desired.

The term "intermediate nozzle" as I understand it, in order to be distinguished from devices of similar appearance but distinctly different use that are sometimes connected with spark arresters and the like, may be defined as follows, with reference to Figures 1 and 2:

In the now most common form of draft appliance, the exhaust steam is discharged from the

nozzle 7 directly into the stack 6, and is in free contact with the surrounding combustion gases while on its way from said nozzle to said stack. The stack is then usually longer, about following the dotted lines 12. The exhaust steam jet, owing to its natural tendency, expands laterally, forming a cone 13. There is not much opportunity for the exhaust steam and the combustion gases to mix thoroughly on the short way between the exhaust nozzle 7 and the stack inlet 12: 10 Steam and gas travel more or less parallel to each other and the stack fulfills also the function of uniformly mixing them which is essential for satisfactory draft-producing action.

Through the introduction of the intermediate 15 nozzle 9, interposed between the exhaust nozzle 7 and the stack 6, the processes of entraining the gases and of mixing them with the steam are divided into two parts. Likewise, the interposition of a number n of such intermediate nozzles would 20 divide said processes into n plus 1 parts. An intermediate nozzle is similarly situated relative to the nozzle preceding it in the course of the exhaust steam flow, as the commonly used simple smokestack 12 is situated relative to its corresponding exhaust nozzle 7 and, in combination with said preceding nozzle, acts analogously to such commonly used smokestack with its corresponding exhaust nozzle. Therefore, an intermediate nozzle may be defined as a partial smokestack, and has an analogous function, namely to promote adequate mixture of the exhaust steam with a part of the combustion gases and to discharge said mixture in form of an orderly stream 25 wholly into the stack or the next intermediate 30 nozzle, where it mixes with an additional amount of combustion gas. It will also be appreciated, and I have proved theoretically, that the device herein defined as "intermediate nozzle" must be of proper proportions in order to fulfill the above 35 functions: Its smallest cross-sectional area must be larger than the outlet area of the nozzle immediately preceding it, while its outlet area must be smaller than the minimum cross-sectional area of the nozzle or stack immediately following it. Its axial length should be at least equal to its minimum diameter since it cannot otherwise afford adequate mixture of gas and steam. The gas passage formed between the inlet of an intermediate nozzle and the outlet of the nozzle 30 preceding it, as well as that formed between the outlet of said intermediate nozzle and the inlet of the nozzle or stack following it must be of substantial size and at least equal to the minimum cross-sectional area of the stack divided 50 by the number of gas intakes n plus 1 as above defined. If these characteristics are not present, the devices referred to cannot act as intermediate nozzles in the proper sense of the word and cannot substantially improve but may even 55 hinder the draft-producing action.

Hitherto, intermediate nozzles, more commonly under the name of draft pipes, lift pipes or petticoat pipes, have often been used for the purpose of dividing the gas intake of the draft 65 appliance, thereby establishing suction at different heights relative to the boiler tube sheet and promoting more uniform draft action on all boiler tubes than obtainable with a single gas intake. With this object in mind, intermediate 70 nozzles have been made with a cylindrical body flaring out somewhat at the bottom in order to safely catch the incoming steam jet. Sometimes it was found that wider exhaust nozzles could be used in connection with such intermediate 75

nozzles, indicating also a saving in exhaust energy; this was particularly true in connection with smokestacks of relatively large cross-sectional area, common on small locomotives. 5 However, on large locomotives where relatively narrow stacks are being used for several reasons, cylindrical intermediate nozzles not only showed but little benefit, but were often detrimental to blast efficiency.

10 Recognizing the need for improvement, frequent attempts have been made to use intermediate nozzles of other than cylindrical shape. The leading consideration has been to restrict the flow within the intermediate nozzle near its 15 outlet in order to increase the speed of said flow as it escapes from said nozzle, expecting that this may promote a more powerful draft. As a rule, these attempts have failed, but the reason therefor has hitherto not been recognized. I have 20 been able to prove that occasional success was attributable to other causes than said principle of restricting the flow.

On the contrary, I succeeded in establishing 25 that an intermediate nozzle should diverge toward its outlet, that is, should provide a gradually increasing cross-sectional area for the flow through it for a substantial part of its length in order to increase the efficiency of a locomotive 30 draft appliance to the theoretical maximum. I have further discovered that this finding can be utilized to construct greatly improved draft appliances since the several objects listed earlier in this specification may be simultaneously effected by so designing and locating such divergent intermediate nozzles in connection with exhaust 35 nozzle and smokestack as will now be described.

Fig. 3 shows the simplest form of my invention. The intermediate nozzle 9 diverges in the direction of the flow through it and is fitted with 40 a considerably flaring intake 15. I prefer to use with said intermediate nozzle, a stack 8 of substantially similar longitudinal shape having likewise a diverging outlet and a widely flaring intake 16, and to form said stack with a short 45 cylindrical portion 17 between the intake and the diverging portion, since I discovered that it is beneficial to let as much as possible of the mixture between gas and steam take place within the narrowest part of the stack. This latter 50 principle also applies to the intermediate nozzle, and a modification incorporating it is illustrated in Fig. 6, showing a cylindrical throat 18 in the nozzle 9a, but it can be seen that such a throat in the intermediate nozzle will tend to reduce the 55 lateral expansion of the steam jet and will therefore require a greater length of the draft appliance which is not always available. The cylindrical portion 17 of the stack, although not having much effect upon the length required for 60 the device, may also be dispensed with if the draft appliance is to be especially short.

The exhaust nozzle 7 as shown is of the well-known slightly converging form, having a cylindrical portion at its outlet. However, I sometimes prefer to make the exhaust nozzle slightly 65 divergent as shown at 19 in Fig. 5: this will give the steam jet the proper conical shape before escaping from the exhaust tip, resulting in the smoothest flow. Diverging exhaust tips have 70 already been used, but for other purposes and without success. Sharp distinction must be made between the function of an exhaust nozzle and that of an intermediate nozzle: the latter serves 75 to mix gas and steam, and a divergent outlet greatly increases its suction power and saves

energy in addition to other functions; an exhaust nozzle, however, primarily serves to let the steam expand properly, and since in a good draft appliance the average exhaust pressure should be well below the so-called critical pressure of 5 about 12 lbs. per square inch, the exhaust steam passage should converge toward the nozzle tip from a purely thermodynamic standpoint. A slight divergence at the outlet will however cause no thermodynamic loss.

10 Returning to Fig. 3: The exhaust tip having the diameter B may be connected with the top of the smokestack having the diameter C by a hypothetical cone 20, which serves as a basis for proportioning my invention. Length A of said cone 15 should preferably be more than four and a half or five times the difference between its maximum and minimum diameter, C minus B. The smokestack should be made as wide at the top as consistent with service requirements well known to 20 those skilled in the art, and the width of the exhaust nozzle may be chosen from experience. In most cases, my invention will permit the use of an exhaust nozzle 1 to 1.5 inches wider than obtained in best established practice.

25 The distance D from the outlet of the stack to the outlet of the preceding intermediate nozzle is what I call the "length of the mixing zone" of 30 said stack, since the combustion gases entering its intake have a chance to mix with the central current while travelling through said distance D. Likewise, E is the mixing zone for the intermediate nozzle. Relative to the outlet diameter, the length of said mixing zone should be greater 35 for the stack than for the intermediate nozzle.

To fully benefit from my invention, the greater 40 part of the mixing between gas and steam should take place near the throat and within the diverging portion of stack and intermediate nozzle, that is, within the distance F and G, respectively. 45 For this purpose, I prefer to provide a diverging portion extending over at least 45% of the length of the above defined mixing zone, but there is usually no reason against adopting a much higher percentage.

45 In accordance with established practice, I give the stack a lesser divergence than cone 20, thereby promoting complete filling by the steam jet and avoiding any down draft from the atmosphere into the smokebox. The stack can also be 50 essentially cylindrical, but a divergence as specified will function better in connection with my intermediate nozzle.

The intermediate nozzle, however, according 55 to my discovery, need not be so completely filled by the steam jet, and there is no tendency of a down draft through it, the pressure being the same at intake and outlet. I give the intermediate nozzle a greater divergence than the stack, and preferably a slightly greater or equal 60 divergence than cone 20. I further make the choke diameter of the intermediate nozzle slightly greater than the adjacent diameter of the cone 20. Thus, I attain a fourfold purpose, namely: 1. I 65 effectively promote lateral expansion of the steam jet, 2. I permit a substantial quantity of gas to pass through the intermediate nozzle, 3. I avoid the striking of the steam jet against the circumferential walls of the intermediate nozzle and the throwing with force of any solid particles 70 against said walls, 4. I attain another new and especially valuable feature of the draft appliance, in that it provides a relatively stronger draft at low running speeds so that the steam pressure 75 will tend to rise when the engine is starting on

a heavy pull, while with the presently known draft appliances the effect is just the opposite.

By considerably flaring the intakes 15, 16 of intermediate nozzle and stack, I catch a substantial amount of combustion gases and drive them securely into the steam jet. Moreover, I provide thereby, a gas passage of ample area around the outlet of the preceding nozzle and insure that the gases are not being forced into the steam jet before they have been accelerated to high speed by the vacuum drawing them toward the throat. In this way I minimize the shock as gas and steam come together, minimizing the resulting losses in energy.

15 The arrows 21, 22 indicate the gas flow toward the intake of stack and intermediate nozzle. While I seek to securely guide said flow, it is obvious that at some distance from the steam jet, the gas flow will take care of itself, and I found it useless to extend the intake of either stack or intermediate nozzle to the plane of outlet of the preceding nozzle, unless there are other reasons for doing so. However, the distance H, K between two adjacent parts of the draft appliance 20 should not be greater than one third to two thirds of the outlet diameter of the preceding nozzle, meaning that said parts should follow each other in close succession.

Naturally, proportions may be changed from 30 those recommended without departing from the spirit of my invention.

Draft efficiency may be further increased while retaining all other advantages of my invention by incorporating in the draft appliance more 35 than one intermediate nozzle of the above described characteristics. Fig. 4 shows two of such intermediate nozzles, 9b and 9c. The same principles that have been explained in connection with Fig. 3 also apply to Fig. 4, and like reference 40 characters are used for corresponding parts. The various parts, exhaust nozzle, intermediate nozzles and stack, may be placed closer together than in Fig. 3. The length of the mixing zone relative to the outlet diameter should be about constant for 45 the intermediate nozzles, whereby they become the longer the larger they are in diameter, as shown in the drawings. It is seldom advisable to use more than two or three intermediate nozzles between exhaust nozzle and stack since their effect 50 is impaired in case they are too short.

If the length of the draft appliance, that is the distance A from the exhaust tip to the outlet of the stack (Fig. 3) is especially restricted, or if a wide stack is desired, my intermediate nozzle may 55 be adapted to split and spread the exhaust steam, whereof Figures 7, 8, and 9 illustrate a preferred example. In said example, the intermediate nozzle 9d (Fig. 7) is split into four parts near the throat, see Fig. 8 showing a cross section along the line 8—8. The four canals 23 so formed leave 60 passages 24 between themselves through which the combustion gases can enter, as best visible in the top view of said intermediate nozzle, Fig. 9. Split intermediate nozzles are known, but before 65 my invention they have been formed with converging or cylindrical circumferential walls, and therefore with an excessively restricted outlet area which together with the tendency of said circumferential walls counteracted the lateral expansion 70 of the steam flow instead of promoting it. If, however, an intermediate nozzle as invented by me is adapted to split the steam, any desirable outlet area may be obtained, a gas passage increasing in cross-sectional area toward the outlet 75 may be provided and the splitting adds to the

tendency of my nozzle to spread the steam over a larger area. Thus, a wide stack may be filled with the smallest degree of coercive action on the steam. With this nozzle, the length A of cone 20 may be made only four times the difference between its maximum and minimum diameter, C minus B, although a greater length is recommended.

It is of course irrelevant for the incorporation of my invention in split intermediate nozzles, 10 whether the splitting is being accomplished by branching the intermediate nozzle as exemplified in Figures 7, 8, and 9, or whether bridges, wedges or other dividing means are placed within the nozzle, leaving the outer walls unbroken. Naturally, 15 also, the canals 23 may be of any number and cross-section. They may, for example, have their edges rounded off as shown in the top view of a modified intermediate nozzle, Fig. 10, which however I cite only as an example but do not recommend since this construction tends to unnecessarily restrict the outlet area. All this is irrelevant, the criterion being that the outer circumferential walls 25, or what remains of them, are formed according to my invention. But I prefer 20 the form illustrated in Figures 7, 8, and 9 wherein four canals are used, substantially a quarter of a circle in cross section, also because this disturbs the steam jet as little as possible and secures most uniform filling of the stack as can readily 25 be understood. I further prefer to contract the gas passages 24 between said canals, toward the center as shown in Fig. 9, whereby excessive spreading of the flow in the center is avoided, which I found very essential.

35 Split nozzles as hereinbefore described may be used singly as in Fig. 7, or two or more may be superimposed like the plain intermediate nozzles in Fig. 4. Furthermore, one or more split nozzles may be arranged in succession with one or 40 more plain nozzles. Whatever arrangement is to be used depends upon the particular problem to be solved, but what has been said hereinbefore about the practical limitation in the number of plain intermediate nozzles applies to an even 45 higher degree to split nozzles: In order to avoid intermediate nozzles which are too short relative to their diameter, it is not advisable to combine such split nozzles with more than one additional intermediate nozzle unless there are other reasons for doing so, for example, unless a larger 50 number of gas intakes is desired.

It is obvious that my invention is not confined to draft appliances of circular cross section, but that it can be applied to other forms, of which 55 the oblong section shown in Figures 11, 12, and 13 is the most important. The principles explained above in connection with devices of circular cross section can be applied here in an analogous manner and the same reference characters are again 60 used, conforming to analogous parts referred to earlier in this specification. The significance of the conoidal body 20 and other analogies will be better understood if it is considered that such oblong draft appliance may be regarded as being 65 made up of a number of circular draft appliances of proportions corresponding to the transverse section Fig. 12, all arranged in line and close together, the adjacent walls of which have been removed. But such oblong draft appliances should be made 70 with a slightly lesser divergence than a circular device.

Intermediate nozzles according to my invention may naturally also be used in any combination with hitherto known intermediate nozzles.

Finally, my invention is of course not confined to the conventional form of locomotive having a cylindrical fire tube boiler and a reciprocating steam propelling engine, but it may be incorporated in any steam locomotive wherein exhaust steam is used for creating draft.

I claim:

1. In a locomotive draft appliance, a stack, an exhaust nozzle and one or more intermediate nozzles therebetween, at least one of said intermediate nozzles having a flaring intake and having circumferential walls diverging toward its outlet, said circumferential walls enclosing a larger cross-sectional area than a hypothetical conoidal body connecting the exhaust nozzle with the top of the stack and having an equal or larger divergence toward their outlet than said conoidal body.
2. In a locomotive draft appliance, a stack, an exhaust nozzle and one or more intermediate nozzles therebetween, at least one of said intermediate nozzles having a flaring intake and having circumferential walls diverging toward its outlet and enclosing a cross-sectional area so much larger than a hypothetical conoidal body connecting the exhaust nozzle with the top of the stack that contact between said walls and the exhaust steam jet is avoided, said circumferential walls having further an equal or larger divergence toward their outlet than said conoidal body.
3. In a locomotive draft appliance, a stack, an exhaust nozzle and one or more intermediate nozzles therebetween, at least one of said intermediate nozzles being adapted to split the exhaust steam and having circumferential walls diverging toward its outlet and a flaring intake, the said circumferential walls of said steam-splitting intermediate nozzle enclosing a larger cross-sectional area than a hypothetical conoidal body connecting the exhaust nozzle with the top of the stack, said circumferential walls having further an equal or larger divergence toward their outlet than said conoidal body.
4. The combination claimed in claim 3, characterized by the fact that the circumferential walls of the said steam-splitting intermediate nozzle enclose a cross-sectional area so much larger than the said hypothetical conoidal body connecting the exhaust nozzle with the top of the stack, that contact between said walls and the exhaust steam jet is avoided.
5. In a locomotive draft appliance, a stack diverging toward its outlet, an exhaust nozzle and one or more intermediate nozzles therebetween, at least one of said intermediate nozzles being

adapted to split the exhaust steam and having circumferential walls diverging toward its outlet and a flaring intake, said circumferential walls enclosing a larger cross-sectional area than a hypothetical conoidal body connecting the exhaust nozzle with the top of the stack and having a greater divergence toward their outlet than the stack. 5

6. In a locomotive draft appliance, a stack, an exhaust nozzle and one or more intermediate nozzles therebetween, at least one of said intermediate nozzles being adapted to split the exhaust steam and having a minimum circumference or throat between its inlet and outlet and providing for the gases a cross-sectional area that is larger at said outlet than at said throat, said stack and steam-splitting intermediate nozzle having circumferential walls diverging toward their outlets, the circumferential walls of said intermediate nozzle diverging more than those of the stack. 10 15 20

7. In a locomotive draft appliance, a stack, an exhaust nozzle and one or more intermediate nozzles therebetween, at least one of said intermediate nozzles being adapted to split the exhaust steam and having a minimum circumference or throat between its inlet and outlet and providing for the gases a cross-sectional area that is larger at said outlet than at said throat, and having circumferential walls enclosing a cross-sectional area so much larger than a hypothetical conoidal body connecting the exhaust nozzle with the top of the stack that contact between said walls and the exhaust jet is avoided, said circumferential walls having further an equal or greater divergence toward their outlet than said conoidal body. 25 30 35

8. In a locomotive draft appliance, a stack diverging toward its outlet, an exhaust nozzle and one or more intermediate nozzles therebetween, at least one of said intermediate nozzles being adapted to split the exhaust steam and having a minimum circumference or throat between its inlet and outlet and providing for the gases a cross-sectional area that is larger at said outlet than at said throat, and having circumferential walls enclosing a cross-sectional area so much larger than a hypothetical conoidal body connecting the exhaust nozzle with the top of the stack that contact between said walls and the exhaust jet is avoided, said circumferential walls having further a larger divergence toward their outlet than the stack. 40 45 50 55
